UNITED STATES PATENT OFFICE.

WILLIAM W. COE, OF SOMERVILLE, MASSACHUSETTS.

DESIGN FOR A MEDALLION.

SPECIFICATION forming part of Design No. 32,379, dated March 27, 1900.

Application filed February 26, 1900. Serial No. 6,640. Term of patent 14 years.

To all whom it may concern:

Be it known that I, WILLIAM W. COE, of Somerville, in the county of Middlesex and State of Massachusetts, have invented and 5 produced a new and original Design for Medallions, &c., of which the following is a specification.

The said drawing represents a plan view of a medallion, showing my new design.

10 As shown in the drawing, the leading or material feature of my design consists of the representation of a four-leaf clover *a*, a rabbit-foot *b*, and a horseshoe *c*, arranged on a field or table which is here shown of circular form. The field is subdivided by radial lines 15 *d* in a series of subdivisions, each containing one of the symbols above mentioned.

This design is intended for coin-shaped pocket-pieces and medallions, and it may also be used in connection with rings, lockets, and 20 other articles.

Having thus described my invention, what I claim as new, and desire to secure by Letters Patent, is—

The design for a medallion or other like article substantially as shown and described. 25

In testimony whereof I have affixed my signature in presence of two witnesses.

WILLIAM W. COE.

Witnesses:

C. F. BROWN,
H. L. ROBBINS.
